CLAIM

The ornamental design for a gun, as shown and described.

DESCRIPTION

FIG. 1 is a right-side elevational view showing my new design;

FIG. 2 is a left-side elevational view thereof;

FIG. 3 is a perspective view thereof;

FIG. 4 is a top plan view thereof;

FIG. 5 is a bottom plan view thereof;

FIG. 6 is a rear elevational view thereof; and

FIG. 7 is a front elevational view thereof;

FIG. 8 is a right side elevational view showing a second embodiment of a gun showing my new design;

FIG. 9 is a left-side elevational view of the gun shown in FIG. 8;

FIG. 10 is a perspective view of the gun shown in FIG. 8;

FIG. 11 is a top plan view of the gun shown in FIG. 8;

FIG. 12 is a bottom plan view of the gun shown in FIG. 8;

FIG. 13 is a rear elevational view of the gun shown in FIG. 8; and

FIG. 14 is a front elevational view of the gun shown in FIG. 8;

FIG. 15 is a right side elevational view showing a third embodiment of a gun showing my new design;

FIG. 16 is a left-side elevational view of the gun shown in FIG. 15;

FIG. 17 is a perspective view of the gun shown in FIG. 15;

FIG. 18 is a top plan view of the gun shown in FIG. 15;

FIG. 19 is a bottom plan view of the gun shown in FIG. 15;

FIG. 20 is a rear elevational view of the gun shown in FIG. 15; and

FIG. 21 is a front elevational view of the gun shown in FIG. 15.
